UNITED STATES PATENT OFFICE

JOHN H. WHITWELL, OF PHILADELPHIA, PENNSYLVANIA

DESIGN FOR WALL PAPER

Application filed May 28, 1929. Serial No. 31,431. Term of patent 3½ years.

To all whom it may concern:

Be it known that I, JOHN H. WHITWELL, a citizen of the United States, residing at Philadelphia, in the county of Philadelphia and State of Pennsylvania, have invented a new, original, and ornamental Design for Wall Paper, of which the following is a specification, reference being had to the accompanying drawing, forming a part thereof,

The figure is a plan view of a piece of wall-paper, embodying the design.

I claim:

The ornamental design for wall paper substantially as shown.

JOHN H. WHITWELL.
